(57) **CLAIM**

I claim the ornamental design for the water cooler, as shown and described.

DESCRIPTION

FIG. 1 is a front view of the water cooler.

FIG. 2 is a rear view of the claimed design.

FIG. 3 is a left side view of the claimed design.

FIG. 4 is a right side view of the claimed design.

FIG. 5 is a top view of the claimed design.

FIG. 6 is a bottom view of the claimed design.

FIG. 7 is an isometric view of the claimed design; and,

FIG. 8 is a cross sectional view thereof taken along line 8-8 of FIG. 1; detailing the shape of each compartment within the chest portion of the water cooler.

1 Claim, 6 Drawing Sheets
